US0D1002490S

(12) **United States Design Patent** (10) **Patent No.:** **US D1,002,490 S**
(45) **Date of Patent:** **** Oct. 24, 2023**

(54) **ROOF PANEL FOR A ROOF ASSEMBLY OF A WORK VEHICLE**

(71) Applicant: **CNH Industrial America LLC**, New Holland, PA (US)

(72) Inventors: **David Sheldon Booth**, Fargo, ND (US); **William Venth**, Chicago, IL (US); **Michael J. Braun**, Oswego, IL (US); **Thomas Michael Curley**, Detroit Lakes, MN (US); **Aaron Francis Onken**, Kindred, ND (US); **David Larry Tveito**, West Fargo, ND (US); **Russell V. Stoltman**, Frankfort, IL (US); **Abhishek Shende**, Vadodara (IN)

(73) Assignee: **CNH INDUSTRIAL AMERICA LLC**, New Holland, PA (US)

(**) Term: **15 Years**

(21) Appl. No.: **29/820,718**

(22) Filed: **Dec. 23, 2021**

(51) LOC (14) Cl. **12-16**

(52) U.S. Cl.

(57) **CLAIM**

The ornamental design for a roof panel for a roof assembly of a work vehicle, substantially as shown and described.

DESCRIPTION

FIG. 1 is a perspective view of a roof panel for a roof assembly of a work vehicle;

FIG. 2 is a back view of the roof panel;

FIG. 3 is a front view of the roof panel;

FIG. 4 is a right side view of the roof panel;

FIG. 5 is a left side view of the roof panel; and,

FIG. 6 is a top view of the roof panel.

In the drawings, the broken lines depict environmental subject matter only and form no part of the claimed design.

1 Claim, 4 Drawing Sheets
